UNITED STATES PATENT OFFICE.

WILLIAM PARKER STRAW, OF MANCHESTER, NEW HAMPSHIRE.

LOOM-SHUTTLE.

1,092,959.

Specification of Letters Patent.

Patented Apr. 14, 1914.

Application filed July 28, 1913. Serial No. 781,487.

To all whom it may concern:

Be it known that I, WILLIAM PARKER STRAW, a citizen of the United States, and resident of Manchester, county of Hillsboro, 5 State of New Hampshire, have invented an Improvement in Loom-Shuttles, of which the following description, in connection with the accompanying drawing, is a specification, like characters on the drawing representing like parts.

This invention relates to an improvement on United States Letters Patent No. 906,748, granted to me Dec. 5, 1908, and Letters Patent No. 1,053,673, granted to me Feb. 18, 15 1913, wherein a bobbin of the type used in shuttles for automatic filling replenishing looms is arranged to be positioned properly when inserted in the shuttle at the time of filling replenishment.

20 As stated in the patents above referred to, one form of bobbin used in shuttles of so-called "feeler" looms is provided with a longitudinal recess or slot in its barrel, over which the filling is wound. When the bobbin is in use the filling is unwound until predetermined exhaustion is obtained. When the slot is uncovered, the feeling device or a part thereof enters it and the desired change in the operation of the loom is 25 effected. Manifestly the slot must be so positioned in the shuttle that it will be directly opposite the feeling device to insure the proper operation of the mechanism, and in my patents aforesaid, I have shown guiding means to coöperate with opposite parallel faces on the bobbin base to insure the correct angular position of the bobbin when presented to the holding jaws of the shuttle.

30 In my present invention I have so mounted the guide members on the jaws that they exert an improved action upon the incoming bobbin, in that they are capable of resilient movement in more than a single plane and more readily rotate a misaligned bobbin 35 into the proper position to be received by the jaws of the shuttle.

40 Shuttles made in accordance with the present invention can be more cheaply constructed and are more easily assembled and 45 repaired than the devices disclosed in the 50 patents above mentioned.

The novel features of the invention will 55 be fully described in the subjoining specification, and particularly pointed out in the following claims.

In the accompanying drawings illustrat-

ing the invention;—Figure 1 is a side elevation of the portion of a shuttle and a bobbin embodying my present invention. The shuttle wall being partly broken away, and the bobbin being shown as about to be transferred to the shuttle. Fig. 2 is a top plan view of the part of the shuttle shown in Fig. 1, the base of the bobbin being shown by dotted lines in the shuttle jaws. Fig. 3 is a 60 longitudinal detailed section on the line 3—3 Fig. 2, showing the manner in which the guides are secured to the holding jaws of the shuttle. Fig. 4 is a transverse section on the line 4—4, Fig. 1 looking toward the 65 left and showing a portion of the hopper which feeds the bobbins in the shuttle.

1 is the base of the filling carrier or bobbin; 2 the usual rings thereon; 3 the barrel having a longitudinal recess 4 adapted to 70 coöperate with a feeler which is not shown, but which may be of any usual construction. The base of the bobbin is so shaped as to present two opposite flat and parallel faces 75 5 beyond the rings, and located on the same 80 sides of the bobbin as the openings of the slot 4. In practice the filling is so wound as to cover the slot 4 until it is woven off to a predetermined extent to permit the feeler, or a part thereof, to enter the slot, hence it 85 is obvious that the bobbin must be properly and accurately positioned when inserted in the shuttle.

The body 6 of the shuttle is of the usual construction, having an opening 7 for the 90 reception of the bobbin and at one end thereof the usual forked spring holding jaws 8, having grooves 9 in their inner faces to engage and hold the rings 2 when the bobbin 95 is transferred by the feeder from the hopper to the shuttle. An inclined guide 10 like that shown in my previous patents is located between the bases of the jaws, and serves to direct the bobbin longitudinally 100 into proper position at the time it is inserted in the shuttle.

In Fig. 4 a portion of the bobbin hopper 11 is shown as provided with peripheral pockets 12 having parallel sides 13 to coöperate with the faces 5 of the bobbin end, 105 and properly position them, prior to their transfer to the shuttles. As the bobbins may turn slightly during the transfer from the hopper to the shuttle, guides 15 are provided within the shuttle which will insure 110 the positioning of the bobbin, so that the same will be grasped by the shuttle jaws

with the slot 4 opposite the feeler-opening 14 in the side wall of the shuttle.

In my present invention each guide 15 is made of a flat reversely curved leaf-spring 5 which is secured by a rivet 16 or other fastener to a holding jaw near its base, and its end 17 made to abut the fork 18 of the said holding jaws 8. The body of the spring is of considerable length and is of substantially 10 the same width as the jaws, but the forward end 19 is broader and projects upwardly a considerable distance above the top of the jaw. The upwardly projecting portion is inclined from its highest point to 15 a point slightly below the plane of the top of the jaw and is bent outward or flared as shown at 20 so as to present a smooth curved edge to the bobbin. The flared portion 20 of the projection 19 extends a considerable 20 distance beyond the plane of the face of the leaf-spring and provides a leverage which when subjected to the pressure of an incoming bobbin causes a twisting movement 25 of the body of the spring in addition to its yielding movement toward the adjacent jaw.

The resilient twisting movement of the guides particularly adapts them to engage the faces of the bobbin end and turn the bobbin into proper angular relation to the guide 30 jaws so that even if the faces 5 of the bobbin are not properly presented when brought into engagement with the guides, the latter will operate to correct such improper positioning before the rings 2 are brought into 35 engagement with the jaws, thus the slot 4 will always be positioned opposite the feeler opening 14 of the shuttle. The flared ends of the guides also form a smooth cam surface for the engagement of the end of the 40 bobbin, and thereby avoid any abrasion or planing of the wood which occurs when the guides present sharp edges to an improperly presented bobbin. By this construction it is not necessary to use metal caps to cover the 45 bobbin ends and a considerable expense in the manufacture of the bobbins is thereby avoided.

The means for securing the leaf-spring to the shuttle jaws is located near the base of 50 said jaws where there is great strength and rigidity, the shuttle jaws not being cut away or otherwise materially weakened by the means for supporting the guide.

The present construction has, in addition 55 to the advantage above specified, that of being more cheaply manufactured and more easily repaired, since each guide is separate

from its companion and is capable of being more easily secured to its shuttle jaw than any of the previous constructions.

Having fully described my invention, what I claim as new and desire to secure by Letters Patent is:-

1. In a loom shuttle having spring jaws adapted to engage and hold the rings on the 60 base of a bobbin provided with parallel and flat faces beyond the rings, a pair of flared spring guides extending longitudinally of, and parallel to said jaws, means for securing each guide to a shuttle jaw so that the same 65 shall be capable of a yielding movement toward said jaw and also of a resilient twisting movement, whereby said guides are adapted to engage the end of the bobbin and rotate and direct the same into proper 70 position between the jaws when the bobbin is inserted in the shuttle.

2. In a loom shuttle having spring jaws adapted to engage and hold the rings on the 75 base of a bobbin provided with opposite 80 parallel and flat faces beyond the rings, resilient guides for the bobbin comprising leaf springs disposed longitudinally of said jaws and secured to the same near their bases, and having upwardly extended inclined and flared ends, whereby said guides are adapted to receive between them said flat faces of the bobbin, and rotate and direct the same into proper position between the 85 jaws when the bobbin is inserted in the 90 shuttle.

3. In a loom shuttle having forked spring jaws adapted to engage and hold the rings on the base of a bobbin provided with parallel and flat surfaces beyond said rings, a 95 pair of resilient guides for the bobbin comprising leaf springs, secured to the respective jaws near their bases, one end of each 100 spring abutting against the fork of said jaws, and the other end of each spring having an upward extension which is inclined and flared outwardly, whereby when a bobbin end is improperly presented said guides are adapted to receive, rotate and direct the 105 bobbin into proper position between the jaws when the bobbin is inserted in the shuttle.

In testimony whereof, I have signed my name to this specification, in the presence of two subscribing witnesses,

WM. PARKER STRAW.
